UNITED STATES PATENT OFFICE.

ALONZO KIMBALL MARSH, OF NEW YORK, N. Y., ASSIGNOR TO A. KIMBALL COMPANY,
OF NEW YORK, N. Y., A CORPORATION OF NEW YORK.

MARKING TICKET.

Application filed August 3, 1922. Serial No. 579,439.

To all whom it may concern:

Be it known that I, ALONZO KIMBALL MARSH, a citizen of the United States, and resident of New York, county of New York, 5 and State of New York, have invented an Improvement in Marking Tickets, of which the following description, in connection with the accompanying drawing, is a specification, like characters on the drawing representing like parts.

This invention has for its object the provision of a pinless marking ticket which can be readily and firmly secured in position on the article or articles to be marked particularly when the said article or articles present a substantial bulk or thickness.

The object of the invention is to provide a marking ticket which may be used without the slightest danger of injury to the most delicate fabrics or articles and which shall remain securely in position without danger of accidental removement or displacement.

The object of the invention is further to provide such a marking ticket of a construction such that it may readily be adjusted to articles of varying sizes.

These and other objects and features of the invention will appear more fully from the accompanying description and drawings and will be particularly pointed out in the claims.

In the drawings;

Fig. 1 is a view in perspective of a portion of a bundle of articles such as neckties with a preferred form of marking ticket embodying the invention in position thereon;

Fig. 2 is a plan view of a marking ticket such as shown in Fig. 1 and embodying a preferred form of the invention;

Fig. 3 and 4 are plan views of slightly different form of the ticket; and

Fig. 5 is an end elevation of a ticket such as shown in Figs. 1 and 2 when bent into its marking position.

The marking ticket of this invention is capable of a wide application of use wherever, in particular, it is desired to mark with suitable indicia, such as price, size, style, etc., etc., one or more articles of substantial thickness or bulk. The marking ticket of this invention is of the general type disclosed in the patent to Wallin 1,073,828 of September 23, 1913. The body of the ticket 55 comprises a plurality of plies of flexible,

non-metallic material such as heavy paper or thin cardboard glued or cemented together with one or more interposed soft wire stiffeners extending longitudinally between the plies. In the patent to Wallin the marking ticket there illustrated is held in place on the article to be marked by being bent around the article and clamped to the article, the soft wire interposed stiffener holding the marking ticket in place. Such a ticket is entirely satisfactory for a wide range of use but when the article or articles to be marked are of substantial thickness or bulk, such for example as a bunch of neckties, a marking ticket such as disclosed in the Wallin patent is likely to become separated from the article or articles to which it has been attached. This is chiefly due to the fact that it is difficult, if not impossible, to give a permanent "set" to the stiffener of the marking ticket unless the marking ticket with the interposed wire stiffener be bent sharply back upon itself which may be readily done in the case of comparatively thin articles or thin packages such as a few layers of fabric.

The present invention provides a marking ticket so constructed as entirely to surround the article or articles to be marked and to be held securely in place by tongue and slot engaging means forming a part of the marking ticket itself.

A simple and preferred form of the invention is illustrated in Figs. 1, 2 and 5. As there shown the body of the ticket is of general rectangular form and comprises two plies or layers 1 and 2 of thin cardboard or thick paper, but as pointed out any number of plies or layers may be employed and any suitable flexible non-metallic material may be employed.

A wire stiffener 3 is interposed between the plies, as between the plies 1 and 2, and extends longitudinally of the ticket preferably in a straight line and centrally of the body. This stiffener is preferably made of a soft wire such as employed in this type of ticket and which retains a permanent set when it is bent or doubled back upon itself. A stiffener of this character when bent sharply and pressed back upon itself will clamp or pinch comparatively thin articles and retain its position thereon. But when it is bent in a wide curve or a wide angle it will not firmly clasp and hold them.

This invention, therefore, provides suitable means for holding the ends of the ticket embodying the wire stiffener in place when the ticket is wrapped around thick articles 5 or a bundle of thin articles. For that purpose the body of the marking ticket presents adjacent one end a transversely elongated aperture 4 preferably formed centrally of the ticket and at the opposite end a tongue 5 containing the end of the wire stiffener and, therefore, preferably formed centrally of the ticket.

The tongue 5 at its base 6 preferably lies within, and is separated by slots 7 from, the body of the ticket and preferably also the tongue projects beyond the body of the ticket as illustrated.

The body of the ticket presents a space of a size depending upon the width of the ticket upon which suitable indicia, such as grade, style, size, price and other marks may be printed or placed.

The ticket is wrapped around the article or bundle of articles to be marked, the wire stiffener being bent as it is thus wrapped around the articles and the end of the tongue is passed through the aperture 4 and bent back sharply upon itself as shown in Fig. 1 thus holding the marking ticket firmly and securely in place, the slots 7 enabling the ends of the body of the ticket to overlap when the ticket is in marking position as illustrated in Fig. 1. The length of the tongue, which preferably is substantial, 35 enables the ticket to be adjusted to the size of the article or articles about which it is wrapped and a further adjustment, enabling the effective surrounding length of the ticket to be varied, is provided by forming a plurality of apertures at the opposite end of the ticket. One such additional aperture is indicated at 8.

The general shape and construction of the ticket may be varied considerably. If 45 desired transverse scores or depressions as

indicated at 9 in Fig. 3 may be provided to enable the ticket readily to be bent into rectangular form and to position the display face of the ticket where appear the suitable indicia. So also as shown in Fig. 4 a plurality of symmetrically situated apertures 10, tongues 11 and stiffening wires 12 may be employed. The number, position and shape of the apertures may be varied and the apertures may extend through the side edges of the tickets enabling the tongues to be placed therein from the edges.

Having thus described my invention, what I claim as new and desire to secure by Letters Patent, is:

1. A marking ticket comprising two plies of flexible non-metallic material secured together face to face, a soft wire stiffener interposed between said plies and extending longitudinally thereof, the said ticket presenting an aperture adjacent one end and a tongue at the other end containing the end of the wire stiffener whereby, when the ticket is bent to surround the article or articles to be marked, it may be secured in position by passing the tongue through the aperture and bending the tongue back upon itself.

2. A marking ticket comprising the construction defined in claim 1 in which the base of the tongue lies within, and is separated by slits from, the body of the ticket thus enabling the ends of the ticket to overlap when in marking position.

3. A marking ticket comprising the construction defined in claim 1 in which the ticket presents a plurality of the said apertures arranged at different distances from the end whereby the effective surrounding length of the ticket may be varied according as the tongue is passed through one or another of said apertures.

In testimony whereof, I have signed my name to this specification.

ALONZO KIMBALL MARSH
